[57] CLAIM

The ornamental design for an electronic system housing for printed circuit boards and power source, as shown.

DESCRIPTION

FIG. 1 is a front elevational view of an electronic system housing for printed circuit boards and power source showing my design;

FIG. 2 is a rear elevational view thereof;

FIG. 3 is a top plan elevational view thereof;

FIG. 4 is a bottom plan elevational view thereof;

FIG. 5 is a right side elevational view thereof;

FIG. 6 is a left side elevational view thereof;

FIG. 7 is a rear elevational view with power supply removed; and

FIG. 8 is a perspective view of a second embodiment wherein the only difference resides in the appearance of the face plate.
